OF NEW YORK, N. Y.

SUPERHEATER

Application filed May 11, 1929, Serial No. 362,336, and in Germany July 18, 1928.

The subject matter of this invention is a steam header for fire-tube superheaters in cases in which the fire-tubes have a staggered arrangement, the connection of the superheater elements being made to the lower side of the steam header. When the bottom of the steam header is a flat surface, this results in the superheater elements having ends of unequal length corresponding to the staggering of the fire-tubes. The result is that the superheater elements of a given tier are not interchangeable with those of an adjacent tier.

This disadvantage is obviated by means of the arrangement in accordance with this invention, which consists in having the surfaces of the header to which the ends are connected stepped to correspond to the staggering of the fire tubes. In this way the ends of the elements pertaining to a given tier of tubes are made of the same length as the ends of the elements in the adjacent staggered tier, so that the elements can be mutually interchanged and the number of kinds of elements or element groups to be kept in stock is reduced.

The steam header according to the present invention is adapted both for superheaters in fire-tubes of normal diameter and for superheaters in enlarged flues and likewise for symmetrical as well as for unsymmetrical tube distribution. In the former distribution, right and left elements have to be dealt with but in the unsymmetrical distribution only right or left elements occur so that in this latter case the number of kinds of elements is further diminished and each element of a tier can be exchanged with the corresponding element of any other tier. The stepped arrangement of the connection surfaces for the superheater elements in accordance with the invention can be effected by forming the bottom of the steam header itself in a stepped manner or by inserting pieces of the proper length between the plane superheater header bottom and the superheater element ends of one set of the staggered rows which are to be connected to the header.

According to one form of the invention, the top of the header is also stepped to corre-

spond to the bottom. This is done where the ends are held to the header by means of bolts extending through the header. The bolts will, by this arrangement, remain of equal length.

The drawings show a few illustrative forms of this inventive idea.

Figs. 1 and 2 show a cross sectional and longitudinal section respectively of a steam header according to this invention in the case of a superheater in normal diametered fire tubes; Figs. 3 and 4 show a form of a header with stepped top; Figs. 5 to 7 show two further forms of the steam header for fire-tubes of normal diameter, while Figs. 8 to 10 illustrate two forms of a header for superheaters in enlarged flues; Fig. 11 also shows a superheater in enlarged flues, this figure showing the form in which the intermediate pieces are used; Figs. 12 and 13 show, on an enlarged scale, different forms of these interposed pieces.

In the case of the superheater in normal diametered fire-tubes as shown in Figs. 1 and 2, the superheater elements 1 are arranged in the fire-tubes 2, the latter having a staggered arrangement. The ends of the superheater elements of two neighboring fire-tube rows are connected to the bottom of the superheater header 5 by means of the angular clamps 3 and the studs 4. The superheater elements pertaining to a given vertical row or tier of fire-tubes are arranged in two groups A and B and are connected to the bottom of the header in such a manner that the connected ends viewed from the smokebox lie one in front of the other (Fig. 2). In order to make the ends, carrying the saturated and the superheated steam respectively, equal in length in each group of elements of a given tier to the corresponding ones in the adjacent staggered tier, the superheater header 5 is provided with connecting surfaces 6 and 7 on its underside, which are relatively stepped corresponding to the staggering of the fire-tubes (Fig. 1). The superheater header 5 may be a single piece or may be made of two separate parts, namely a central superheater chamber 8 and two lateral saturated chambers 9 connected by

means of the bridge 10. In the form shown in these figures, the fire-tubes are symmetrical with regard to a vertical plane through the axis of the boiler so that there will be right and left elements. For each element group A and B there will therefore be required two kinds of elements, one right and one left. In the group of right-hand elements or in the group of left-hand elements, the elements of each group of a given tier are interchangeable with the corresponding elements of any other group, since the ends of these elements or element groups are of the same length. If the header had a plane connection surface, there would be four sorts of elements, namely, right-hand and left-hand elements, and in each of these groups two elements with unequal ends.

In the form of the invention shown in Figs. 3 and 4, the ends of the superheater elements 1 are connected to the header 5 by means of the ordinary clamps 3' and thru-bolts 11. In order to make it possible to use bolts of the same length, the header 5 is formed on its upper side with surfaces 12, 13 which are stepped to correspond to the steps 6, 7 of the bottom and with which the nuts of the bolts 11 contact. The tube sheet shows an unsymmetrical arrangement of fire-tubes, so that there is only one kind of elements, that is, either right-hand or left-hand. If, therefore, the elements of a given tier are gathered again into two groups as in the case first described, then there will be only one sort of elements in each group, that is, either right-hand or left-hand elements, so that each group belonging to a given tier can be exchanged for the corresponding one of any other tier.

The forms of the invention according to Figs. 5 to 7 show a header 5 in which the number of steps in the bottom and top is smaller. The connection surfaces 6 and 7 are chosen so that to each surface the ends of superheater elements 1 of two adjacent fire-tubes 2 may be secured. This results in a tube sheet with a staggered square arrangement of flues and if the distribution is symmetrical there will be only one sort of elements, namely right-hand or left-hand. This staggered square distribution is a cross between the pure square arrangement and the pure staggered arrangement.

Fig. 7 shows the same tube arrangement as Fig. 5 but the ends of the superheater elements 1 are secured by means of thru-bolts. Accordingly the header 5 is stepped on top by means of the steps 12 and 13 to correspond to the steps 6, 7 of its bottom.

Fig. 8 shows a header 5 for a superheater in enlarged flues with unsymmetrical distribution. The arrangement of the steps on the bottom of the header is such that right and left-hand elements of two adjacent tiers are required. The arrangement has the advan-

tage that there will be very wide passages for the gases.

A further form of the invention in connection with superheaters in flues of enlarged diameter is shown in Figs. 9 and 10. Here the steps 6, 7 on the floor or bottom of the header are so arranged that only left or only right elements are required. The header 5 has two chambers 9 for saturated steam and one chamber 8 for superheated steam. In this form the elements of a given staggered tier can be exchanged for elements of the corresponding elevation in any other tier.

In the superheater for enlarged flues shown in Fig. 11, the floor or bottom 14 of the header 5 is plane. In order, still to obtain stepped connecting surfaces for the element ends, connecting pieces 15 of proper length are inserted above the lower tiers. These pieces are provided at their lower ends with the connecting surfaces 16 which are stepped as compared with the connecting surfaces 6 of the bottom 14. To secure the element ends of two adjacent rows, the angular clamps 3 are used, which are drawn up by means of the studs 4 and thereby force the element ends against the connecting surfaces 6 and 16. In the form according to Fig. 12, the intermediate pieces 15 are loosely interposed. When the nuts of the studs 4 are drawn up, the conical surfaces 17 are forced into the hollow conical seats 6 of the header bottom 14. In this form of the invention the bottom of the header is therefore modified in no way and yet the new form of staggered connecting surfaces and element ends of the same length are used instead of the former arrangement of element ends of unequal length in which all the connecting surfaces were in one plane in the superheater header bottom. Fig. 13 shows a form of the invention in which the intermediate pieces 15' are screwed into the floor 14 of the header. Obviously any other appropriate means of securing these intermediate pieces in the floor might be used. For instance, the intermediate pieces might be welded into the bottom.

We claim:

1. In apparatus of the class described, the combination of a flue sheet, flues extending back from said flue sheet, said flues lying in relatively staggered vertical rows, groups of tubular superheater elements located in said flues with their ends extending out of the front ends of said flues, a superheater header parallel to and forward of the flue sheet and above the flues, connecting seats being provided to which the element ends are connected to put them into communication with the interior of the header, said seats being located in horizontal rows above the vertical rows of flues to which they respectively correspond and each end of each group of elements occupying an entire row of seats, the rows of seats having a stepped arrangement corre-

sponding to the staggering of the flues whereby the horizontal rows of seats are all at the same vertical distance above their associated vertical rows of flues and the groups of tubes are all alike.

5 2. Apparatus in accordance with claim 1, the stepping of said seats being effected by stepping the bottom of the header.

10 3. Apparatus in accordance with claim 1, the apparatus further comprising angular clamps engaging the element ends, and screw means engaging the clamps and forcing them toward the header.

15 4. Apparatus in accordance with claim 1 and in which the wall of the header opposite the seats is stepped similarly to the latter wall and means including bolts all of the same length for pulling the element ends toward the header.

20 5. In apparatus of the class described, the combination of a flue sheet, flues extending back from said flue sheet, said flues lying in relatively staggered vertical rows, tubular superheater elements located in said flues with ends extending out of the front ends of said flues, a superheater header parallel to and forward of the flue sheet, connecting seats being provided to which the elements' ends are connected to put them into communication with the interior of said header, said seats lying on surfaces having a stepped arrangement corresponding to the staggering of the flues whereby the seats are all the same distance from the associated flues, the wall 25 of the header opposite the one containing said seats being stepped similarly to the latter, clamps engaging the ends of the superheater elements, and bolts all of the same length and extending through the header and engaging the clamps to pull them and the elements 30 toward the header.
